UNITED STATES PATENT OFFICE.

ELI PERRY, OF BALDWINSVILLE, NEW YORK, ASSIGNOR TO HIMSELF AND JOHN BOLEY, OF SAME PLACE.

IMPROVEMENT IN ROTARY PUMPS.

Specification forming part of Letters Patent No. 36,588, dated September 30, 1862.

To all whom it may concern:

Be it known that I, ELI PERRY, of Baldwinsville, in the county of Onondaga and State of New York, have invented a new and useful Improvement in Centrifugal Pumps; and I do hereby declare that the following is a full and exact description thereof, reference being had to the accompanying drawings, making part of this specification.

Figure 1 is a vertical section of the case inclosing the piston, in the plane indicated by the red line, Fig. 2, and showing the actuating parts in elevation; Fig. 2, a plan of the case; Fig. 3, a plan of the inner side of the upper half of the case, together with the piston.

Like letters designate corresponding parts in all the figures.

My invention consists in the combination, with a case provided with an increasing spiral discharge-passage, of a piston having radially-curved and transversely-concave wings, and an induction-feeder extending through the top of the case, the whole arranged and operating substantially as hereinafter described.

The case in which the piston plays is of the ordinary form and construction, being composed of an upper and lower half, A and B, which are counterparts, fitting together and secured by means of bolts passing through the flanges *a a*, with packing between, in the usual manner. The shape of the case is eccentric, and it is provided at the proper position with a circular spiral water-discharge passage, D, commencing at a point at the abutment *b* (where the piston touches) and gradually increasing in diameter around the central circle till at the ejection-outlet C the eccentricity is equal to the diameter of the passage at that point. The central portion of the case, or that portion in which the piston turns, is made dishing, as represented at *c c*.

The piston is composed of a center having radiating wings E E E, curved longitudinally in the direction opposite their motion, so as to present a convex outline on the acting side and concave in cross-section on the same side, as represented at *d*. This concavity extends the whole length, and is sufficient to correspond nearly with the circularity of the discharge-passage D. Any desired number of wings may be used, three only being represented in the drawings. Their length is such

as to just reach to the abutment *b* and to fill the radius of the central circular dishing portion, *c*, of the case, between the opposite sides of which they closely but easily fit, so that but very little escape is allowed around them. On top of the piston is situated a central circular induction-feeder, G, of suitable size and height for the purpose designed, extending upward through an opening in the upper half of the case, and provided with as many open mouths or passages *h h h* as there are wings in the piston. These passages are inclosed at the side and top, the covering of the latter inclining from the forward edge downward as it extends backward, in such a manner as to draw and direct the water into the case as the feeder is revolved, as represented most clearly in Fig. 1. The piston and feeder are actuated by a shaft, H, whose lower bearing, *f*, rests in a suitable step in the center of the closed lower half, B, of the case, and which extends upward to the top of the well and is connected with suitable gearing, that represented in the drawings being a pinion, K, on its end, meshing with a cog-wheel, L, driven by a winch, M, the whole being supported by a suitable frame, N. The pump thus arranged is worked below the surface of the liquid that it raises. The rapid motion of the piston throws the water in the case outward into the spiral discharge-passage D, where, by the centrifugal action, it passes around to the ejection-pipe. The peculiar shape of the wings is best adapted to the purpose, as the friction or resistance of the water thereon is reduced to the minimum degree. The concavity transversely gives a roundness or circularity to the body impelled into the discharge-passage, corresponding in form with the same, and the radially-curved shape, while giving a tendency to throw the water outward more readily into the passage, allows it to escape much more easily than if the wings were plane and straight. In addition to this centrifugal action, the rapid motion of the feeder G is constantly forcing the water downward, thus keeping a continual and unvarying pressure within the case, and assisting the raising of the liquid. The induction-passages *h h* of the feeder open at the bottom, respectively, directly into the angles formed at the base of the adjacent wings, and in such a direction that the current is not turned acutely and

suddenly by the contact, but by a regular and easy deflection, and so as to receive the best impelling action from the said wings with the least amount of friction. By being carried around by the feeder while entering the case the liquid also receives the initiatory motion necessary to its easy and forcible discharge into the exit passage. By the combined action of the feeder and piston the water is thus raised in the simplest and most effective manner, with the smallest amount of friction and with the least expenditure of power compatible with the result produced. The feeder by being situated in the top of the case (the bottom being entirely closed) draws the liquid in only from above and not from below, as usual. This prevents in a great degree the introduction to the case of dirt, sand, or other substance that is liable to be drawn in from the bottom. The arrangement is particularly applicable to use in breweries, where the sediment forms thickly in the bottoms of the tanks, and which would choke any pump with the induction at the base. I have applied the device to this use, and find it to perfectly

answer the purpose. The general construction, also, is such as to insure the best result when applied to this use, as there are no valves or other parts to become easily obstructed. As the feeder is revolved rapidly, the liquid entering the induction-passage has a tendency to raise the same, thus counterbalancing to a certain degree the weight of the shaft H and decreasing the friction on the bearing f.

I do not claim separately either the piston or feeder; but

What I claim as my invention, and desire to secure by Letters Patent, is—

The combination, with the spiral discharge-passage D, of the piston provided with curved concave wings E E and the feeder G, the whole arranged and operating substantially as and for the purposes herein set forth.

In witness whereof I have hereunto signed my name in the presence of two subscribing witnesses.

ELI PERRY.
